UNITED STATES PATENT OFFICE.

JAMES L. HAMILTON, OF GRAND JUNCTION, COLORADO.

ORCHARD-HEATER.

1,088,658.

Specification of Letters Patent.

Patented Feb. 24, 1914.

Application filed April 19, 1913. Serial No. 762,294.

To all whom it may concern:

Be it known that I, JAMES L. HAMILTON, a citizen of the United States of America, and resident of Grand Junction, county of 5 Mesa, and State of Colorado, have invented certain new and useful Improvements in Orchard-Heaters, of which the following is a specification.

This invention relates broadly to heating 10 apparatus, and specifically to a novel and improved construction of orchard heater.

The primary object of the invention is to provide an orchard heater of the oil-burning type which is specially designed for burning 15 liquid fuel or oils of low grade, as asphaltum oils.

In burning low grade liquid fuels, as asphaltum oils, in vessels wherein the flame is permitted to play over the entire surface, 20 the richer, or more volatile, portion, which is uppermost in the vessel, burns first; thus the grade of the fuel becomes poorer as the bottom of the vessel is approached, resulting in combustion or vaporization of the fuel 25 becoming slower and the heat generated gradually growing less.

It is therefore an object of this invention to provide an orchard heater wherein the flame is permitted to play over a relatively 30 small part only of the surface of the oil in the container, or vessel, and wherein the oil is permitted to feed to the combustion point from the bottom of said container, resulting in the grade of the fuel supplied to the burning 35 point being maintained substantially uniform until all is consumed.

A further object of the invention is to provide a heater of the character mentioned in which a blast of air is directed upon the surface 40 of the burning oil, resulting in said oil burning with a blow torch effect.

With these and other objects in view, the invention resides in the construction, arrangement and combinations of parts herein- 45 after described and illustrated in the accompanying drawings, in which—

Figure 1 is a top plan view of the invention; Fig. 2 is a longitudinal section of the same, taken on the line 2—2, Fig. 1; Figs. 3 50 and 4 are transverse sections taken, respectively, on the lines 3—3 and 4—4, Fig. 1; Fig. 5 is a section on the line 5—5, Fig. 2, showing a modified form of guides for the damper; Fig. 6 is a section somewhat similar to Fig. 2, showing a plurality of draft 55

tubes; and Fig. 7 is a view somewhat similar to Fig. 4, illustrating a modification.

Referring to said drawings, in which like reference characters distinguish like parts throughout the several views—1 indicates an oil receptacle, or container, which is herein shown as being rectangular in shape, but which may be of any other suitable form. Removably mounted upon the top of said container is a shield 2 of downwardly dished, 60 or pan-like, form having laterally directed terminal flanges 3 which rest upon and project laterally beyond the top edges of the container. Extending downward through an opening provided therefor in the bottom 65 of said shield or pan 2 adjacent to one end of the latter is a sheet metal fire-box 4, open at both ends, which has a peripheral outwardly directed flange 5 at its upper end mounted upon the bottom of said pan about 70 the opening in the latter, whereby said fire-box is suspended from said pan with its lower end elevated slightly above the bottom 75 of the container.

Resting upon the flanges 3 of the pan is a lid or cover 6, herein shown as flat, which has its lateral longitudinal edges turned under, as shown at 7, to constitute guideways in which the longitudinally extending flanges 3 of the pan are received, said cover 80 thus being adapted for sliding longitudinally with respect to said pan in effecting the mounting and removal thereof. Provided in said cover over the position occupied by the fire-box 4 is one or more draft-openings 85 8 designed to admit air to said fire-box for facilitating combustion of fuel contained in the latter. The volume of air permitted to enter the fire-box is controlled by a regulating damper 9 which is slidably mounted in a 90 position permitting of closing off of one or all of said openings. As shown, said damper is slidable between a pair of oppositely disposed guide-flanges 10 mounted on opposite sides of said draft opening, or 100 which may be formed by striking up strips of metal from said cover in a well-understood manner, as shown at 10^a in Fig. 5. A collar 11 is formed on said cover 6 about an opening provided in the latter at the end 105 opposite that which overlies the fire-box, and mounted about said collar is a tubular pipe or stack 12 through which the products of combustion from the fire-box are discharged, said products being directed thereto through 110

the space afforded between the cover 6 and the bottom of the pan, as indicated by arrows in Fig. 2.

As fuel is consumed in the fire-box, oil is fed thereto from the container, the oil level in said fire-box and container being obviously maintained equal. And, since the oil supply to the fire-box must enter through the lower end thereof, which closely approaches the bottom of the container, it will be understood that the entrance of the lighter, most volatile portion, which lies on the surface, prior to the heavier bottom oil is prevented, and that, as a consequence, the quality of the oil supplied to the fire-box will be maintained substantially uniform until all has been consumed.

For facilitating combustion when the fuel has burned down somewhat, that is, when the fuel lowers to a point where the drafts of air entering through the draft-openings 8 do not strike forcibly upon the surface of the fuel—a draft tube is provided, the same being suspended from and opening through the cover 6, whereby air is conducted close to the surface of the oil. When the oil has burned down, uncovering the lower end of such draft-tube, the air rushes through said tube in the form of a blast, producing upon the surface of the oil a flame which resembles or closely approaches that of a blow-torch. The fuel in the fire-pot is thus vaporized and burned rapidly, producing a high degree of heat in which the carbon and other smoke and smut producing elements is largely consumed, but little smoke and smut being permitted to issue from the stack.

It will be obvious that a plurality of draft tubes as 13 and 13^a and having different lengths may be projected into the fire-pot as shown in Fig. 6 so that they may be successively uncovered as the fuel is lowered.

While it is not the purpose of the device to heat and vaporize the fuel contained in the receptacle or container outside the fire-pot, some gas is of course generated within said container. To permit this gas to escape, an opening 14 is provided in the bottom of the pan, preferably at a point directly in line with the center line of the stack.

While the cover 6 is shown to be flat in Figs. 1, 2, 3, 4 and 6, the same may, if desired, be made in the same form as the pan 2—that is, dished as shown at 6^a in Fig. 7—55 in which case it will be disposed in a reversed position when mounted in place, thus increasing the capacity of the passageway for the products of combustion from the fire-pot to the stack, as is clearly illustrated in said Fig. 7.

Having thus described my invention, what I claim as new, and desire to secure by Letters Patent, is—

1. An orchard heater comprising an oil container, a downwardly dished shield

mounted over said container, a fire-pot projected through and depending from said shield adjacent to one end thereof, a cover mounted over said shield and supported at a distance from the bottom of the latter, said cover having closable draft-openings therein over the position occupied by said fire-pot, and a stack mounted on said cover at a point remote from said draft-openings. 70

2. An orchard heater comprising an oil container, a downwardly dished shield mounted over said container, a fire-pot projected through and depending from said shield adjacent to one end thereof, a cover mounted over said shield and supported at a distance from the bottom of the latter, said cover having closable draft-openings therein over the position occupied by said fire-pot, a tube depending within said fire-pot from said cover, and a stack mounted over said cover at the end opposite that which overlies the fire-pot. 75

3. An orchard heater comprising an oil container, a downwardly dished shield mounted over said container, a fire-pot projected through and depending from said shield adjacent to one end thereof, a cover mounted over said shield and supported at a distance from the bottom of the latter, damper-controlled draft openings in said 90 cover over the fire-pot, means for directing blasts of air directly upon the surface of the oil in the fire-pot, and a stack located on said cover at the opposite end of the latter. 95

4. An orchard heater comprising an oil container, a downwardly dished shield mounted over said container, a fire-pot projected through and depending from said shield adjacent to one end thereof, a cover mounted over said shield and supported at a distance from the bottom of the latter 105 whereby a passageway is afforded between them for the products of combustion from the fire-pot, damper-controlled draft-openings in said cover over the fire-pot, and a 110 stack mounted upon the end of the cover opposite that which overlies the fire-pot and having communication with said passageway.

5. An orchard heater comprising an oil container, a downwardly dished shield mounted over said container, a fire-pot projected through and depending from said shield adjacent to one end thereof, a cover mounted over said shield and supported at a distance from the bottom of the latter 115 whereby a passageway is afforded between them for the products of combustion from the fire-pot, damper-controlled draft-openings in said cover over the fire-pot, a tube 120 for conducting air directly to the surface of the oil in the fire-pot, and a stack communicating with said passageway to permit products of combustion to issue therefrom. 125

6. An orchard heater comprising an oil 130

container, a downwardly dished shield mounted over said container, said shield having laterally projecting flanges along its longitudinal edges, a fire-pot projecting through and depending from said shield, a cover mounted over said shield and having turned-under longitudinally extending edges in embracing slidable relation to the shield flanges, regulatable means for admitting air to the fire-pot, and a stack mounted on said cover at a point remote from the fire-pot.

In testimony whereof, I affix my signature in presence of two subscribing witnesses.

JAMES L. HAMILTON.
